Arthur Warne

By Alexander M. Mason

UNITED STATES PATENT OFFICE.

ARTHUR WARNE, OF BUFFALO, NEW YORK.

FIRE-BOX FEEDER.

SPECIFICATION forming part of Letters Patent No. 236,385, dated January 4, 1881.

Application filed July 6, 1880. (Model.)

To all whom it may concern:

Be it known that I, ARTHUR WARNE, of Buffalo, in the county of Erie, and in the State of New York, have invented certain new and useful Improvements in Fire-Box Feeders; and I do hereby declare that the following is a full, clear, and exact description thereof, reference being had to the accompanying drawings, and to the letters of reference marked thereon, making a part of this specification.

This invention relates to an improved apparatus for feeding disintegrated or finely-commiuated fuel—such as sawdust, tan-bark, and the like—to furnaces by means of a forced blast of air; and it has for its objects to provide means by which the air required to carry the fuel may be reduced in volume previous to entering the furnace without loss of the fuel, as more fully hereinafter specified. These objects I accomplish by the mechanism illustrated in the accompanying drawings, in which—

Figure 1 represents a perspective view of my apparatus, and Fig. 2 a longitudinal vertical section thereof.

The letter A indicates a horizontal tube, constructed of metal or other suitable material, having a bend, B, about midway between its ends. To the forward end of the said tube 30 is adjustably secured an enlarged distributing-chamber, C, which projects through an opening, D, or the door of a furnace. The said tube, at its rear end, is provided with a vertical extension, E, from the top of which extends 35 a segmental tube, F, connecting with the main tube A just at the upper part of the bend thereof. The said extension E is open at one side, as indicated by the letter G, for the purpose hereinafter explained.

40 The letter H indicates an opening leading into the rear end of the tube A, by which the said tube is connected to the fuel-supply tube leading from the fan or other blast-generator, by which the air and fuel are forced to the furnace. The horizontal tube A, at the top of that portion located between the upright extension E and the connection of the segmental tube F, is open, and is provided with a series 45 of deflectors. The said deflectors are in the form of pivoted valves, as indicated by the letter A', in the latter case being connected by a suitable link or links, I, with a bent le-

ver, K, fulcrumed in standards L, whereby they may be operated simultaneously, for the purpose hereinafter set forth.

55 The distributing-chamber C is provided at each side, near its mouth, with pivoted valves M, secured to the operating-levers N, by which they can be opened or closed to any desired extent.

60 The operation of my invention is as follows: The blast of air, with the fuel, is forced into the opening at the rear of the tube A and passes forward into the same. On its passage it meets the inclined deflectors, and by them 65 is deflected backward, causing a portion to escape, while the fuel, owing to its weight, is thrown to the bottom of the tube and is carried forward by the diminished blast to the furnace. In case the deflectors or valves are 70 opened to such an extent as to permit the escape of a portion of the fuel, such escaping fuel will be carried back to the open side of the vertical extension, and will enter the same and find its way back to the horizontal tube, 75 through the segmental tube before mentioned, the current of air through the horizontal tube serving to induce a current through the segmental tube and upright extension sufficient 80 to carry the fuel through the same.

Having thus fully described my invention and the method of its operation, what I claim, and desire to secure by Letters Patent, is—

1. In combination with the horizontal feed-tube, the hinged deflectors A' A', the connecting-link I, and bent lever K, the whole 85 adapted to operate substantially as specified.

2. In combination with the horizontal tube and its deflectors, the vertical extension, with the blowing apparatus and segmental tube, 90 whereby any escaping fuel is taken up and returned to the horizontal tube, substantially as specified.

3. In combination with the horizontal tube, the distributing-chamber and its valves for directing the fuel into the furnace at any desired angle, substantially as specified.

In testimony that I claim the foregoing I have hereunto set my hand this 28th day of June, 1880.

ARTHUR WARNE.
